PARAFFIN CUTTER

Duel J. McDuffie, Plaquemine, La.

Application March 11, 1957, Serial No. 645,156

6 Claims. (Cl. 166—176)

This invention comprises a novel and useful improved paraffin cutter and more particularly relates to an apparatus and method for removing the paraffin deposits which customarily form in the flow lines and tubing of oil wells.

A very serious problem attending the pumping and flowing of petroleum through a tubing or flow line of a flowing or pumped oil well is the deposition of paraffin upon the internal walls of the tubing and flow lines as the paraffin condenses or precipitates out of the more volatile liquid oil during the passage of the latter through the tubing or flow line. As these paraffin deposits build up upon the interior of the tubing or flow line, they restrict the cross sectional internal diameter of the latter to such an extent as to seriously hamper and in some instances entirely prohibit the flow of oil through the flow line or tubing; and in other instances seriously interfere with or prevent the operation of a pump and the pumping rods in the tubing. When this condition arises, it has been heretofore frequently necessary to pull the tubing or flow line from the well in order to remove the paraffin and restore the well to production; or to resort to various more or less expensive operations for mechanically or chemically cleaning the paraffin deposits from the same.

It is therefore a primary purpose of this invention to provide an apparatus and a method whereby such paraffin deposits may be quickly and readily removed from the tubing or flow line to thereby restore the same to normal operation; and whereby this object may be readily and quickly effected in an improved manner.

A further object of the invention is to provide an apparatus and method which shall be effective for removing paraffin deposits despite any quantities which may be present in or occur in the tubing or flow line.

A still further object of this invention is to provide an apparatus and a method whereby a pump rod string or the like may be employed for moving the paraffin cutter through a flow line or tubing and whereby the resiliency of the cutter may accommodate the latter to inequalities in the internal diameter or surface of the flow line or tubing and enhance the efficiency of operation of the device.

A still further important object of the invention is to provide a paraffin cutter having a plurality of longitudinally spaced, substantially circular, resilient cutter blades thereon which will be of extremely simple and inexpensive construction and yet highly efficient for the purpose intended.

These together with other objects and advantages which will become subsequently apparent reside in the details of construction and operation as more fully hereinafter described and claimed, reference being had to the accompanying drawings forming a part hereof, wherein like numerals refer to like parts throughout, and in which:

Figure 1 is a view in vertical section showing a por-

2

tion of a well bore having a flow line or tubing therein and showing a preferred embodiment of paraffin cutter in accordance with this invention operatively disposed therein for cleaning paraffin from the interior of the tubing;

Figure 2 is a perspective view of the paraffin cutter of Figure 1;

Figures 3—5 are horizontal sectional views taken substantially upon the planes indicated by the section lines 10 3—3, 4—4 and 5—5, respectively, of Figure 2 and showing upon an enlarged scale the structural details and particular mounting of the individual cutters of the device;

Figure 6 is an elevational view of a second embodiment of a paraffin cutter in accordance with this invention, but having a single, rigid, annular cutter blade thereon;

Figure 7 is a horizontal sectional view taken substantially upon the plane indicated by the section line 20 7—7 of Figure 6, but upon an enlarged scale;

Figure 8 is a fragmentary view similar to Figure 1 and illustrating a first step in the method of cleaning paraffin from flow line or tubing in accordance with this invention and in which the undersized, annular, 25 rigid cutter glade is passed through the tubing to remove the major portion of the paraffin deposits but that leaves a thin coating thereof on the internal wall of the tubing;

Figure 9 is a view similar to Figure 8, but showing 30 the manner in which a second rigid, annular cutter blade, in accordance with Figure 6, of substantially the same diameter as the internal diameter of the tubing is passed through the latter to complete the removal of the paraffin therefrom by removing the thin coating left by the step of Figure 8;

Figure 10 is a view similar to Figure 8, but showing 35 an alternative method wherein the second step is performed by the annular, resilient cutter blade of the embodiment of Figures 1—5; and,

Figure 11 is a detail view in vertical section, taken 40 substantially upon the plane indicated by the section line 11—11 of Figure 7 and upon an enlarged scale.

Referring first to the embodiment of Figures 1—5, it will be seen that the numeral 10 designates the casing 45 of a producing well, which may be either a flowing well or a pumped well, and in which is disposed a pump tubing or flow line 12. Indicated by the numeral 14 is the lower portion of a pump rod string or a tool string, to which is secured the paraffin cutting tool 50 indicated generally by the numeral 16 of this invention. It will be understood that in the operation of removing paraffin deposits from the interior of a flow line or tubing 12, the tool 16 is secured to the end of a pump rod string 14 or tool spring and is then passed downwardly and then upwardly through the tubing, whereby to scrape the paraffin deposits from the internal wall of the same.

Referring now more particularly to Figure 2, it will 55 be seen that the paraffin cutter 16 includes a shaft or arbor 18 having a diametrically enlarged upper portion 20 provided with an externally threaded upper extremity 22 whereby the same may be connected to the pump rod string 14 in any conventional manner or to a wire line.

Referring now especially to Figures 3—5, it will be 60 seen that the arbor 18 has secured thereto a plurality of substantially annular or circular cutters, three being shown in Figure 2, and which are indicated generally by the numerals 24, 26 and 28.

Each of the resilient cutters 24, 26 and 28 is of identical construction, these cutters differing from each other solely

in their positioning upon the arbor as set forth herein-after. Accordingly, the same numerals designate the same parts of each cutter and its mounting.

Each of the cutters comprises a single resilient, but stiff wire comprising an intermediate arcuate portion 30 which is concentric to the axis of the arbor 18 and extends throughout the major portion of its length, as, for example, between the points 32 and 34, and is shown in Figures 3-5; this intermediate portion extends through at least 270° of the circumference of the arbor. The intermediate portion at the points 32 and 34 is provided with terminal portions 36 and 38 which extend radially inwardly towards the arbor 18. The junction of the terminal portions with the ends of the intermediate portion thus provide rounded radially outwardly projecting points 32 and 34. Each of the terminal portions is attached to the arbor 18. Thus, for each of the cutters 24, 26 and 28, there is provided a pair of longitudinally spaced, diametrically extending bores 40 and 42 which are closely adjacent to each other, but spaced slightly longitudinally of the arbor and are disposed perpendicularly with respect to each other, as shown in Figures 3-5. The terminal portions 36 and 38 are provided with end portions 44 and 46, respectively, which extend through these bores and have flattened extremities 48 and 50. It will be observed by reference to Figure 3 that the terminal portions 36 and 38 overlap each other.

As so far described, it will thus be apparent that each of the cutter blades comprises a resilient annulus which extends entire about the arbor, the major portion of this annulus being at a constant radius from the center of the arbor, and there being a slight recess between the points 32 and 34 where the terminal portions 36 and 38 cross each other.

It is intended that the resilient cutter blades 24, 26 and 28 shall be of slightly greater diameter than that of the tubing or flow line in which the same are to be utilized in order that the inherent resiliency of the material of the cutter blades will resiliently place the intermediate portion 30 thereof into a scraping contact with the wall of the flow line or tubing. Inasmuch as the major portion 30 of each blade is supported solely by the two resilient arms formed by the terminal portions 36 and 38, it is evident that the blade is flexibly supported upon the arbor with a greater flexibility than could be obtained from a support at both sides of the arbor, whereby a stiffer material can be employed for the cutter blade.

It will be observed next by comparing Figures 3, 4 and 5 that successive blades 26 and 28 have their sets of bores 40 and 42 and their sets of terminal portions 36, 38 and ends 44 and 46 spaced at slightly less than 90° circumferentially of the arbor from those of the immediately adjacent cutter blade. This provides that the portion of the internal wall of the flow line or tubing which is not scraped by the blade which lies between the points 32 and 34 of one blade will be engaged by the intermediate portion of the other blades to thus comprise a complete overlapping action of the blades on the wall of the flow line or tubing.

It will thus be understood that there has been provided a highly effective paraffin cutter, which by virtue of its unusual resiliency as to construction and mounting will accommodate itself to irregularities in the internal diameter of flow lines or tubing, will compensate for any out-of-round conditions therein, and can be inserted in pipes having smaller diameters than that of the intermediate portion 30.

Referring next to Figures 6 and 7, there is disclosed a modified construction of paraffin cutter, which, in place of the resilient circular cutter of the embodiment of Figures 1-5, employs a rigid circular blade thereon. In this embodiment the cutter includes an arbor 60 which is externally threaded as at 62 at its upper end for reception in a box 64 having a pin 66 adapted to be secured

to the end of a pump rod string or tool string such as that indicated at 14 in the preceding embodiment.

At its lower end, the arbor 60 is provided with rigid radially extending arms 68 and an annular band 70 is secured thereto as by welding or the like. This band and also the arms 68 are provided with a depending annular knife edge 72 as will be apparent from Figure 11. If desired, as shown in Figure 7, the arm 68 may extend slightly beyond the band 70, whereby to space the latter slightly from the internal walls of a flow line or tubing.

Referring now to Figure 8, there is disclosed an embodiment similar to that of Figures 6 and 7 and which embodiment is substantially identical with that of my prior Patent No. 2,521,076. This particular form of cutter is identical with that of Figures 6 and 7, except that the arbor 80 thereof is integral with the diametrically enlarged upper portion 82 and which is adapted to be secured to the lower end of the pump rod string or tool string previously mentioned. As in the embodiment of Figures 6 and 7, the radially extending arms 86 and the annular rim 88, having a knife edge 90 thereon, are identical with the arms, rim and knife edge, 68, 70 and 72, of the preceding embodiment. However, in this form, the annular blade, instead of being welded to the arms 68, is secured to the arbor as by nuts 92 carried by the diametrically reduced, externally threaded portion 94.

The preferred method of cleaning paraffin from a flow line or tubing in accordance with this invention is as follows, reference being made particularly to the views of Figures 8-10. In Figure 8, the flow line or tubing 12 is shown with an internal deposition of paraffin in the form of a coating or lining 96. While the view indicates the coating as being substantially regular in its nature, it is to be understood that actually paraffin deposits are usually irregular in nature and may be of any magnitude up to substantially entirely bridging and closing the internal diameter of the tubing.

As the first step of this invention, there is secured to the end of the string 14 a paraffin cutter in which the annular cutter blade is of slightly less diameter than that of the interior of the tubing 12. Thus, when the cutter is passed through the tubing, it will remove the major portion of the paraffin deposit, but will leave a relatively thin film or coating, as at 98, which may be of the order of about one thirty-second of an inch in thickness. The purpose of this is to permit the use of a relatively heavy and rigid cutter for removing the major portion of the paraffin, and in order to permit the use of the rigid cutter, the same must be of a less diameter than the wall of a bore in order to permit the device to be passed through a tubing which may be out-of-round or have other surface irregularities therein which would prevent the passage of a cutter having a close fit with the wall of the tubing.

Illustrated in Figure 8 is that form of paraffin cutter shown and claimed in my above mentioned prior patent. It will be understood, however, that the same may be, in some instances, of the form shown in Figures 6 and 7, while in further instances satisfactory results may be obtained by use of the cutter of Figures 1-5.

After the undersized cutter has been run through the pipe, as in Figure 8, the same is removed and to the string 14 is attached a second cutter, such as that shown in Figures 6 and 7. The second cutter, however, is of substantially the same internal diameter as the tubing 12, as indicated in Figure 9, is employed to scrape away the remainder of the paraffin constituted by the thin coating of sheaf 98 left by the first cutter.

Alternatively, as shown in Figure 10, in place of the rigid cutter shown in Figure 9, the second step of the method may be performed by the resilient cutter of Figures 1-5. As the latter is passed through the tubing 12, its resilient annular cutter elements 24, 26 and 28 will remove the thin film or coating 98. During this operation, that portion of this thin film, as at 100, which may

have passed or been left by the opening between the points 32 and 34 of one of the annular resilient cutter blades, as shown in Figure 10, will be removed completely by succeeding blades.

The foregoing is considered as illustrative only of the principles of the invention. Further, since numerous modifications and changes will readily occur to those skilled in the art, it is not desired to limit the invention to the exact construction and operation shown and described, and accordingly all suitable modifications and equivalents may be resorted to, falling within the scope of the invention as claimed.

What is claimed as new is as follows:

1. A paraffin cutter for oil well tubing comprising an arbor, means for connecting said arbor to a means for vertical reciprocation in said tubing, a plurality of resilient cutters secured to said arbor in longitudinally spaced position thereon, said arbor having a pair of substantially perpendicular, diametrically spaced bores for each cutter, each cutter comprising a separate substantially circular wire having a single convolution about said arbor and having a pair of ends secured in said pair of bores.

2. The combination of claim 1 wherein successive pair of bores are disposed at successive angular intervals to each other circumferentially of said arbor.

3. The combination of claim 1 wherein each cutter has its end portions overlapping each other and in spaced relation longitudinally of said arbor.

4. The combination of claim 1 wherein each cutter has an intermediate circular portion surrounding the

major portion of the circumference of the arbor and radially inwardly directed terminal portions, the terminal portions overlapping and having their ends extending through and secured in said pair of bores.

5. The combination of claim 1 wherein each cutter has an intermediate circular portion surrounding the major portion of the circumference of the arbor and radially inwardly directed terminal portions, the terminal portions overlapping and having their ends extending through and secured in said pair of bores, the junction of the intermediate portion with the terminal portions providing a pair of rounded, radially outwardly projecting points.

6. The combination of claim 1 wherein each cutter has an intermediate circular portion surrounding the major portion of the circumference of the arbor and radially inwardly directed terminal portions, the terminal portions overlapping and having their ends extending through and secured in said pair of bores, each cutter projecting from one terminal portion both circumferentially and longitudinally of the arbor to its other terminal portion.
